UNITED STATES PATENT OFFICE.

CLEVELAND W. COLE, OF SPOKANE, WASHINGTON, ASSIGNOR TO COLE DUPLEX AUTO SIGNAL COMPANY, OF SPOKANE, WASHINGTON, A CORPORATION.

DESIGN FOR AN AUTOMOBILE-SIGNAL-LAMP CASING.

54,064.

Specification for Design.

Patented Nov. 4, 1919.

Application filed May 14, 1919. Serial No. 297,170. Term of patent 7 years.

To all whom it may concern:

Be it known that I, CLEVELAND W. COLE, a citizen of the United States, residing at Spokane, in the county of Spokane and State of Washington, have invented a new, original, and ornamental Design for an Automobile-Signal-Lamp Casing, of which the following is a specification, reference being had to the accompanying drawing, forming a part thereof.

The first figure is an elevation of the auto signal lamp casing, and

The second figure is an edge view of the same, showing my new design.

I claim:

The ornamental design for an automobile signal lamp casing, substantially as shown.

CLEVELAND W. COLE.
